W. J. TANGERMAN

TANK CAR CONSTRUCTION

Filed May 28, 1921

Fig. 1

Fig. 2

Inventor:
William J. Tangerman
By *Arthur M. Nelson his Atty.*

UNITED STATES PATENT OFFICE.

WILLIAM J. TANGERMAN, OF HAMMOND, INDIANA.

TANK-CAR CONSTRUCTION.

Application filed May 28, 1921. Serial No. 473,238.

To all whom it may concern:

Be it known that I, WILLIAM J. TANGERMAN, a citizen of the United States, and a resident of Hammond, county of Lake, and State of Indiana, have invented certain new and useful Improvements in Tank-Car Constructions, of which the following is a specification.

My invention relates generally to improvements in tank cars but relates more particularly to improvements in the outlet or lading egress parts thereof.

Railroad tank cars are used for carrying a wide variety of products, ranging from free flowing liquids such as gasoline, benzine, turpentine and the like, to such heavy and normally semi-solid materials such as tar, heavy oils, greases and the like. Because of the fact that some of the materials to be carried flow reluctantly, if at all, at normal temperatures, and for other reasons, it is necessary to provide for the heating of the contents of the tank car. In tank car outlets heretofore provided, it is also customary to apply heat thereto which is done by surrounding the same with steam or other heating jackets. Also because of the fact that tank cars are heated from time to time there is considerable expansion and contraction of the car tank which has necessitated the provision of special fastening means between the tank and the car underframe to admit of this wide range of movement on the part of the tank without shearing or otherwise injuring the fastening or tank anchorage. While these tank car anchorages are sufficient to retain the tank upon the car underframe in normal operation, in the event of a wreck it is quite likely

that the tank will separate from the car underframe, particularly if the tank is loaded. Furthermore when the tank is thus torn from the underframe it usually will be found that the tank car outlet has either been entirely torn away or else that it has been bent or ruptured to such an extent as to cause leakage of the contents. Hence, it is not at all uncommon, under such circumstances, to lose the entire contents of the car.

Thus it appears that, under the conditions that now prevail, separation of the tank from its underframe; separation of the underframe from the trucks; or derailing of the car, not only results in damaging or wholly destroying the tank car outlet but

also usually causes a loss of contents of the car which may amount to many thousands of dollars.

The general object of my invention is to provide a tank car construction which shall practically eliminate all danger of injury to the outlet portion thereof. 60

A further object of my invention is to provide a tank car outlet construction which can be utilized with or upon tank cars of the usual construction, and which shall not require any modification in the manner of anchoring the tank upon the underframe. 65

It is also an object of my invention to provide a tank car outlet construction which shall be of such form and character that the contents of the car can be maintained readily at proper flowing temperature at the outlet or lading egress opening to the end that the discharge of the contents can be 75 rapidly accomplished.

It is also an object of my invention to provide a tank car outlet construction which shall be simple both as to manufacture and as to application to the car tank, and which shall require the withdrawal of the car from service for but a relatively short time when it is to be applied to a car in service. 80

My invention consists generally in the form, arrangement, construction, positioning and co-action of the parts whereby the above named objects, together with others that will appear hereinafter are attainable, and my invention will be more readily understood by reference to the accompanying 85 drawings which illustrate what I consider, at the present time, to be the preferred embodiment thereof.

In said drawings:

Fig. 1 is a transverse sectional view 95 through the tank car outlet portion of a tank car embodying my invention, taken substantially along the line 1—1 of Fig. 2: and

Fig. 2 is a fragmentary side elevation of 100 that part of the car shown in Fig. 1.

No attempt has been made to illustrate the tank car anchorage nor many of the details of the tank car construction inasmuch as these are or may be of the usual construction. However, the car center sill is shown and here takes the form of the two spaced channel members 1 and 2. 3, represents the car tank which is suitably mounted on the car underframe so that at its 105 110

lower point it is somewhat above the upper faces 4 and 5 of the channel member forming the center sill. In the bottom of the tank, and usually substantially midway thereof, will be found an opening 6 which is closed by the flange fitting 7 that is riveted to the tank, and which contains a removable bushing 8, usually formed of brass, to provide a suitable seat for the valve 9. It will be understood that the valve 9 has a long stem 10 which usually extends to the upper part of the tank to enable convenient manipulation of the valve, and also that the valve 9 when closed effectually prevents the flow of any material through the opening 11.

12 represent the tank car heating coils which may be of usual or desired construction but which usually will be found in practice to be distributed relatively close to the tank wall and along the bottom portion thereof. Under the practice heretofore prevailing the tank car outlet has extended into the space between spaced parts forming the center sill, here represented by the channel members 1 and 2, or in any event have extended below the upper face of the center sill so that any transverse shifting of the tank on the underframe has resulted in damage to the outlet, before referred to. To overcome the objection referred to I have provided a pan shaped member which, as here shown, is composed of a bottom portion 13, end wall portions 14 and 15, and side wall portions 16 and 17, which portions terminate outwardly in a flange 18 that is formed to the curvature of the tank 3 and which is securely fastened thereto. The fastening means here shown take the form of a plurality of rivets 19, although the flange may be welded or secured to the tank in any other suitable way. For the sake of a convenient term the member just described will be referred to as a pan. The pan, as shown, forms a relatively shallow chamber, which, because of its proximate relation to the tank and the heating coils therein, is maintained at such temperature as to insure the free flowing of the discharging contents, under all conditions.

For the discharge of the lading, i. e., car contents, from the pan chamber I have provided two lading egress openings 20 and 21 which are tapped with standard pipe threads so that they may be closed by the pipe thread plugs 22 and 23. The pan, as here shown, is a pressed steel plate, and, in order to provide a suitable thickness of material for the plugs 22 and 23, I have secured plates 24 and 25 to the end walls 14 and 15. These plates are shown as being welded to the pan but if desired they may be riveted or otherwise suitably secured.

As is indicated by the extension lines 26

and 27 all parts of the pan, reinforcing plates, plugs, etc., are positioned above the top of the car sill so that they will not engage the sill in the event of a wreck or transverse shifting of the tank. Because of the shallow nature of the pan and the manner in which it conforms generally to the contour of the car tank, the danger of breakage is remote, indeed, so much so, that to all intents and purposes it is non-breakable. 75

The bottom wall of the pan is preferably formed upwardly so as to bring the flow line of the lading substantially on a line with the bottom part of the lading egress 80 openings of the pan.

When the car is to be unloaded either or both of the plugs 22 and 23 are removed and a standard pipe inserted. Of course, if desired, a special fitting can be inserted if a special pipe or other connection is to be used. The valve 9 is entirely protected on the pan and cannot be injured from without. 85

The many advantages of this simple non-breakable tank car outlet construction will 90 be understood, by those skilled in this art, without further comment.

I claim:

1. In a tank car, a sill, a tank having a lading egress opening therein, a pan secured to the tank, surrounding said tank lading egress opening and extending over said sill, said pan having a lading egress opening which is above the top of the sill and beyond the outer side thereof. 95

2. In a tank car, a sill, a tank having a lading egress opening therein, a pan secured to the tank, surrounding said tank lading egress opening and extending over said sill, said pan having lading egress openings in opposite portions thereof. 100

3. In a tank car, a sill, a tank having a lading egress opening therein, a pan secured to the tank, surrounding the lading egress opening and extending over said sill, said pan having an end portion and being provided with a lading egress opening in said end portion, said lading egress opening being above the sill and beyond the outer side thereof. 110

4. In a tank car, a sill, a tank having a lading egress opening therein, a pan secured to the tank, surrounding the lading egress opening and extending over said sill, said pan having an upwardly and outwardly extending end portion and being provided with a lading egress opening in said end portion. 115

5. In a tank car, a sill, a tank having a lading egress opening therein, a pan secured to the tank, surrounding the lading egress opening and extending over said sill, said pan having an inclined end portion and being provided with a lading egress opening in said end portion. 125

6. In a tank car, a sill, a tank having a lading egress opening therein, a pan secured to the tank, surrounding the lading egress opening and extending over said sill, said pan having inclined end portions each provided with a lading egress opening. 25
7. In a tank car, a sill, a tank spaced above the sill and having a lading egress opening therein, a pan secured to the tank, surrounding said lading egress opening, all of said 10 pan being above the top of said sill. 30
8. In a tank car, a sill, a tank spaced above the sill and having a lading egress opening therein, a pan secured to the tank, surrounding said lading egress opening, all 15 of said pan being above the top of said sill, said pan also having a lading egress opening therein. 35
9. In a tank car, a tank having a lading egress opening therein, a pan, secured to the tank and surrounding said lading egress opening, said pan having an end portion provided with a lading egress opening, and a bottom portion formed on a line above the 20 40
- lowermost part of the end portion to provide for drainage. 45
10. In a tank car, a sill, a tank spaced above the sill and having a lading egress opening therein, a pan secured to the tank, surrounding said lading egress opening, extending beyond the outer sides of the sill, and having a lading egress opening in a portion which is beyond the outer side of the sill. 50
11. A tank car construction embodying 35 therein a car sill, a tank mounted upon said sill, having a valve controlled unloader duct, or lading egress opening, arranged in the bottom of the tank, a shallow pan shaped member, secured to the outer side of said tank in position to enclose said valve controlled unloader duct, said pan shaped member extending over the sills and having a lading egress opening therein which is above the sill and beyond the outer side thereof. 45

In testimony whereof, I have hereunto set my hand, this 24th day of May, 1921.

WILLIAM J. TANGERMAN.
